SNACK SERVER

George Kasperan, Jr., 4 Christopher Drive,
Rockville, Conn. 06066

Filed Apr. 21, 1969, Ser. No. 16,824

Term of patent 14 years

Int. Cl. D7—99

U.S. Cl. D44—10

FIG. 1 is a perspective view of a snack server showing my new design;

FIG. 2 is an enlarged scale left side elevational view;

FIG. 3 is a rear elevational view thereof; and

FIG. 4 is a top plan view thereof.

I claim:

The ornamental design for a snack server, as shown.
